EXERCISING MACHINE

James H. Atcheson, deceased, late of Detroit,
Mich., by Louise A. Atcheson, administratrix,
Detroit, Mich.

Application May 25, 1934, Serial No. 727,479

4 Claims. (Cl. 272—69)

This invention relates to exercising machines and particularly exercising machines of a tread mill type.

An object of the invention is to adapt a machine of the tread mill type to be mounted at selective inclinations, so that the weight of a person using the machine may serve to a desired extent to induce belt travel of said machine.

Another object is to provide in a simple manner for regulating belt tension in such a machine.

A further object is to provide hand rails to steady a user of a tread mill exerciser, and to provide for accommodating said rails to the height of the user.

Still another object is to provide such a machine with an endless belt of improved construction.

These and various other objects the invention attains by the construction hereinafter described and illustrated in the accompanying drawing, wherein:

Fig. 1 is a top plan view of the improved machine, with portions broken away.

Fig. 2 is a view of the machine in side elevation, with parts broken away.

Fig. 3 is a cross sectional view of the machine, taken on the line 3—3 of Fig. 1.

Figs. 4 and 5 are vertical sectional views of a socket wherein a hand rail is vertically adjustable.

Fig. 6 is a fragmentary sectional view of a portion of a preferred endless belt.

In these views, the reference character 1 designates a pair of horizontally elongated side boards which are spaced apart by a pair of cross boards 2, substantially equidistant from the ends of the machine. Bridged across said cross boards are a board 3 and a pair of wooden strips 4, spaced from the board 3, at each side of the latter, the members 3 and 4 preferably projecting some distance beyond the cross boards. The members 1, 2, 3 and 4 form the frame of the machine, said members being rigidly connected by screws, 4a, 45 or other suitable means.

Mounted between each strip 4 and the board 3 is a row of rollers 5, individually journaled on pins 6, jointly carried by the members 3 and 4, said rollers being proportioned to project slightly above said members.

Traveling on said rollers is the top span of an endless belt 7, strongly reinforced by tread members 8 formed by strips of wood or other suitable material extending completely across the belt. Preferably said belt is formed of two thick-

nesses of canvas or the like, connected at suitable intervals by transverse seams 9, as best appears in Fig. 6, the outer thickness having sufficient slack between the seams to form sockets snugly receiving the tread members.

The belt is mounted at each end on a pair of pulleys 10, fast upon the end portions of a shaft 11, journaled in bearings 12 carried by the side plates. One of said shafts, with its bearings is made adjustable lengthwise of the frame by locating said bearings in slots 13 in the side boards, and attaching said bearings to metal plates 14 bolted exteriorly against the side boards and slotted lengthwise of the latter to accommodate the bolts 15. Thus tension of the belt 7 may be accurately regulated. The rollers 5 extend substantially between the vertical axial planes of the pulleys 10 so that the top span of the belt is firmly supported throughout its extent. The belt and its tread members are held slightly spaced from the side boards by annular flanges 16 on the pulleys 10.

A pair of arched hand rails 17 are rigidly secured to the side boards 1, so that a person using the machine may grasp same to hold himself steady. The ends of said rails are set into socket members 18 exteriorly secured to said boards, and are preferably adjustable in said socket members to establish the rails at a desired height. Thus the rail end portions may be notched at 19, and the socket members may carry plungers 20 which are normally spring-urged to engage certain of said notches, but may be pressed sufficiently inward to release the hand rails.

It is preferred to incline the machine so that the weight of a user will induce travel of the belt, and it is further preferred to render the inclination variable to control the velocity at which the belt tends to travel. Thus one end of the frame is provided with a pair of legs 21 which engage in socket members 22 secured exteriorly to the side boards and are notched at 23 to coact with plungers 24 for a vertical adjustment, as described in connection with the hand rails.

The described machine is particularly suited for children's use, furnishing both exercise and recreation.

It is a feature of the machine that no spaces are left either between the tread members or between the latter and the frame, sufficient for insertion of a child's finger.

The invention is presented as including all such modifications and changes as come within the scope of the following claims.

What is claimed:—

1. In a tread mill exerciser, a frame comprising a pair of spaced side members, a pair of spaced shafts journaled in said side members, a pair of 5 annularly flanged spaced pulleys mounted on each of said shafts, an endless belt mounted on said pulleys and bridged across each pair thereof, and restrained from lateral shifting by the flanges of said pulleys, and anti-friction means 10 carried by said frame in supporting relation to the top span of said belt.
2. In a tread mill exerciser as set forth in claim 1, a plurality of reinforcing tread members exteriorly carried by said belt and elongated transversely thereof.
3. In a tread mill exerciser, the combination with a frame comprising a pair of spaced side members, a pair of spaced cross members disposed between and rigidly connecting said side members, and a plurality of members bridged between said cross members, of a pair of parallel shafts mounted in the end portions of said side members, a pair of pulleys mounted on each shaft between the side members of the frame, said cross members being disposed between the two pairs of 20 pulleys, and said bridging members projecting 25

terminally beyond the cross members and between the paired pulleys, a plurality of rows of rollers journaled in and between the bridging members, and an endless belt mounted on said pulleys and bridged across each pair thereof, the upper span of said belt resting on said rollers.

4. In a tread mill exerciser, the combination with a frame comprising a pair of spaced side members and a pair of spaced cross members disposed between and rigidly connecting the side members, of a pair of parallel shafts mounted in the end portions of the side members, pulleys on said shafts between the side members, an endless belt mounted on the pulleys, said cross members extending between the upper and lower spans of 15 the belt and between the pulleys carried by the paired shafts, a plurality of rollers journaled upon the frame, beneath the upper span of said belt, and supporting said span, throughout substantially its entire longitudinal extent, and 20 means for holding one end of said frame elevated above the other end thereof.

LOUISE A. ATCHESON,
Administratrix for the Estate of James H. Atcheson, Deceased. 25
